UNITED STATES PATENT OFFICE

2,604,943

MACHINE TO CUT INSULATED BRICK OR
SAND COATED SIDING

John P. Brown, Sunbury, Pa.

Application February 7, 1949, Serial No. 74,896

2 Claims. (Cl. 164—73)

1

This invention relates to novel and useful improvements in cutting apparatus.

An object of this invention is to cut various articles by means of retaining the article to be cut on the top of a table or support and passing a blade or cutter holder having a cutter therein over the material to be cut, the holder being slidably disposed on the article holder.

Another object of this invention is to provide a simplified and improved device of the nature to be described which is used for the purpose of cutting insulated bricks, sand coated siding and any other element adaptable for use in conjunction with the cutting machine by clamping the article and passing a holder thereover in cutting relationship therewith, the holder being mounted on the clamp for retaining the article to be cut and including rollers for facility in movement thereof, the actual movement being imparted by manual means or by motor operated means.

Ancillary objects and features of novelty will become apparent to those skilled in the art, in following the description of the preferred form of the invention, illustrated in the accompanying drawings, wherein:

Figure 1 is a side view of the preferred form of the invention;

Figure 2 is a fragmentary side view similar to that shown in Figure 1, showing a second operative position of the elements;

Figure 3 is a plan view of the device shown in Figure 1;

Figure 4 is a sectional view taken on line 4—4 of Figure 1 and in the direction of the arrows;

Figure 5 is a sectional view taken on line 5—5 of Figure 2 and in the direction of the arrows;

Figure 6 is a sectional view illustrating details of the cutter holder and taken on line 6—6 of Figure 2 and in the direction of the arrows;

Figure 7 is an elevational end view of the device shown in Figure 1 and taken substantially on the line 7—7 of Figure 1 and in the direction of the arrows;

Figure 8 is a sectional view illustrating details of construction of a pair of cams used in conjunction with the invention;

Figure 9 is a sectional view of the cutter mechanism and taken on line 9—9 of Figure 2 and in the direction of the arrows; and,

Figure 10 is a sectional view taken on the line 10—10 of Figure 3 and in the direction of the arrows.

The table 10 is provided with a lateral portion 12 having a number of ribs 14 on the upper sur-

face thereof. The material which is to be cut is disposed on this table top. A plurality of legs 18 having suitable bracing attaching them to the table is provided.

5 A standard 20 including sides 22 and 24 respectively and a spacer 26 is provided at one end and on the upper surface of the table 10. A drive shaft 28 is mounted for rotation in suitable bearings in the sides 22 and 24 and has a pinion 30 at one end thereof. At the other end there is a pulley 32 adapted to have a belt entrained therearound which is also entrained around the drive pulley of a conventional motor. A handle 34 for manual operation is also fixed to the drive shaft 28.

10 The pinion 30 is enmeshed with the gear 36 which is mounted on a shaft 40. The shaft 40 is also disposed for rotation in the sides 22 and 24 respectively. A drum or reel 42 is mounted on the shaft 40 and has a cable 44 wound therearound. A ratchet 46 is fixed for movement with the reel 42 and a dog 48 is pivoted to the side 24 engageable with the ratchet. The ratchet serves in its conventional capacity.

15 Spaced from the standard 20 is a bracket 47 which mounts an idler pulley 50 which is on an idler shaft 52. The idler shaft is maintained in place in the bracket through the medium of conventional pins 49 or the like. The said cable 44 is disposed on the idler pulley 50 thereby guiding the same.

20 As is shown in Figure 1 there is provided a cable clamp 54 at the free end of the cable which is attached to a tool holder or carriage generally indicated at 56. It is apparent now that upon rotation of the drive shaft 28 either by manual means or by a motor the tool holder or carriage 56 may be pulled toward the drum 42 which has the said cable 44 wound therearound.

25 A guide and clamp bar 58 and 60 respectively are maintained in spaced relationship by a pair of spacer plates 62 and 64 respectively. These spacer plates are fixed to the guide bar and to the clamp bar by means of nuts and screws extending therethrough and provided in one of a number of apertures in order that adjustability between these two bars 58 and 60 respectively may be effected. These bars are maintained in place on the table 10 by means of a bolt (Figure 5) 70 which has a wing nut 72 at one end and a yoke 74 at the other end. This yoke extends around the bottom portion of the clamp bar 60 and is pivoted thereto by means of a conventional pin 76. A compression spring 78 is disposed in concentric relationship with the bolt

55

70 and reacts on the undersurface of the table 10 as well as the upper surface of the wing nut 72. Hence, the compression of the spring 73 may be regulated as may be the efficacy of the holding properties of this mechanism.

A standard 80 is fixed to the table 10 as by means of bolts 82 or the like and has a plate 84 rigidly fixed to the top thereof. In this plate there is a slot (unnumbered) and the spacer plate 64 is disposed in this slot. Hence, lateral movement of the guide and holder bars is materially obviated.

Means is provided for raising and lowering the two bars 58 and 60 respectively not only for placing an article to be cut in the proper position but also for the purpose of moving them to the desired position when performing special and cutting operations. This means may be seen best in Figures 6-8. A suitable support such as a pair of uprights 90 and 92 respectively is fixed to the end of the table opposite that having the winding mechanism thereon. A stub shaft 94 is mounted for rotation in these uprights and has a handle 96 fixed to one end thereof. Intermediate the ends is a pair of cams 98 and 100 respectively. One of the cams operates on a finger 102 which is fixed to the spacer plate 62 (Figure 8), while the other cam engages the spacer plate 62 (Figure 2) when the two bars 58 and 60 respectively are held in the down position. This tends to hold the two bars firmly in place. Also to materially reduce side or lateral thrust is a stay rod 108 fastened at its ends to brackets 110 and 112 respectively which are in turn mounted on the lowermost bar 60.

The structure of the carriage includes a tool bar 114 having cutters 116 therein being fixed in place by any suitable means such as set screws or the like. The cutters are mounted in tandem in order that upon movement of the carriage 56 the second and third tools will track with respect to the first tool.

Brackets 118 and 120 respectively are fixed to the tool bar 114 and mount wheels 122 and 124 for rotation. These wheels are preferably of the ball bearing type and they engage the undersurface of the guide bar 58. Hence, upon movement of the cable 44 around the drum 42 the carriage or tool holder is slid smoothly in a predetermined direction. A slide is formed on the lower surface by means of notched plates 126 which are attached to the tool bar by means of bolts or the like. These slides move across the upper surface of the clamp bar 60 as the wheels 122 and 124 respectively are operated.

In order to assist in retaining the material stationary while it is being cut one or more angle irons 130 may be fixed to the upper surface of the table 10 by any suitable means such as bolts or the like.

In operation the handle 96 is motivated to lift the two bars 58 and 60 respectively. The dog or ratchet pawl 48 is removed from the ratchet 46 and the carriage is moved in such direction as to extend the cable from the reel. The sheet of material to be cut is now placed on the table against the angle 130 and the line of cut is located. Then, the cams are rotated to the position as shown in Figure 2 and then will clamp the sheet of material to be cut to the bench preparatory to cutting. Then, either manually or through the medium of a motor the cutter mechanism is pulled over the sheet. Then, upon releasing the sheet from the bench, the device is in readiness for a second cutting operation.

In order to cut a sheet in order that it may fit the pitch of a roof, the sheet is first marked at each end and laid on the table. The marks are spotted with the cutter block and then the cutter block is pulled to one end of pair of bars 58 and 60. The cams are then operated so that the sheet of material is clamped firmly to the table and the reel is operated in order to perform the cut. The handle 140 is employed for returning the carriage.

In order to cut a sheet of material for the purpose of applying it around a window frame, the sill line is marked and then the casing line is marked and both lines are squared. Then, 15 a special chisel-shaped blade is disposed along the point in the corner formed by intersecting lines made after squaring, and by means of a hammer it is driven downwardly to the sheet on both lines. Then, by means of the handle 136 which is mounted for rotation on the table and has a cam 138 thereon (Figure 10), engaging the bar 60, the two bars are lifted. The sheet of material is placed on the bench and the long point (notice different length of cutters in Figure 1) is placed in the holes made by the chisel and hammer. Next, the lever 136 is operated again whereby the two bars firmly maintain the sheet of material in place. By operation of the drum the cutter carriage is moved across the sheet to be cut and there will appear a clean cut corner.

While there has been described and illustrated but one form of the invention, it is apparent that variations may be made without departing from the spirit of the invention. Accordingly, limitation is sought only in accordance with the scope of the following claims.

Having described the invention, what is claimed as new is:

1. In a cutting apparatus, a table having a slot therein, a clamp disposed on said table and including an upper and lower rails, means including a cam for clamping one end of said clamp on said table in releasable fashion by engagement with and between said upper and lower rails, a carriage with a knife holder having a plurality of blades removably disposed therein, said carriage being mounted for sliding movement on said upper and lower rails, said blades depending from said holder unequal amounts and lying along a line parallel to the line of travel of the carriage, the blade at the front of the movable carriage being shorter than the next adjacent blade, means for driving said carriage along said rails on said clamp to cut a sheet of material retained under said clamp, means including a spring and an elongated member resiliently holding the end of said clamp opposite said cam on said table, at which time the lower end of the rearmost of said blades is disposed in said slot.
2. In a cutting apparatus, a table having a top, a clamp disposed on said table top, said clamp including an upper and a lower rail, means holding said rails in spaced relationship with respect to each other, means disposed at one end of said clamp and engageable with said rails between said rails for releasably holding said clamp in such position as to hold an article on said table top, resilient means disposed at the other end of said clamp fixing said other end of said clamp to said table top, a carriage forming a tool holder slidably mounted on said clamp and between said rails, a plate having a slot therein and forming part of said carriage, said lower rail

being disposed in said slot to prevent lateral separation of said carriage from said rails, means secured to said carriage for manually operating said carriage, blades carried by said tool holder and lying along a line parallel to the line of travel of the carriage, and the blade at the front of the carriage being shorter than the next adjacent blade.
